UNITED STATES PATENT OFFICE.

ROY W. H. CRABB, OF BATTLE CREEK, MICHIGAN.

CONFECTION-MACHINE.

No. 829,097.

Specification of Letters Patent.

Patented Aug. 21, 1906.

Application filed December 4, 1905. Serial No. 290,262.

To all whom it may concern:

Be it known that I, Roy W. H. CRABB, a citizen of the United States, residing at Battle Creek, in the county of Calhoun and State 5 of Michigan, have invented a new and useful Improvement in Confection-Machines, of which the following is a specification.

This invention relates to a machine for forming a confection resembling somewhat in 10 appearance that of an ordinary doughnut, and consisting of a suitable base of confection having nuts, puffed rice, or the like stirred therein.

The object of the invention is to shape and 15 form the candy into what I term "fritters" and to deliver the same to suitable pins upon which they are stacked or to packing-boxes when it is desired to box the fritters as soon as finished.

20 The invention consists of a plurality of hinged boards adapted to fold upon a fixed board and upon each other, the boards when folded forming the molds, and a hinged board provided with suitable means for removing 25 the finished article from one of the first-mentioned boards.

In the drawings forming a part of this 30 specification, Figure 1 is a perspective view of my complete device. Fig. 2 is a detail sectional view taken through two of the molds, a portion of one of the boards being shown in dotted lines in position to have the finished product forced upon certain pins.

In the drawings, A represents a suitable 35 platform or table having an elevated central portion A', upon which rests a suitable board or rectangular frame B, upon which are placed a plurality of short upright posts B'. Hinged to the board B is a board C, which 40 has a plurality of circular openings C' formed therein and equal in number to the posts B'. The openings C' are preferably three inches in diameter and the board C one inch in thickness. Adjacent the bottom of the board 45 when in position shown in Fig. 2—that is, when folded upon the board B—the openings C' are provided with a one-fourth of an inch flange C², which reduces the diameter of the openings C' to two and one-half inches. The 50 posts B' are preferably about one inch in diameter; but it will be understood that the dimensions may be varied at pleasure, and the relative proportions above given are not followed in the sectional view. (Shown in Fig. 55 2.) Hinged to the board B on the side oppo-

site the board C is a board D of the same size, and this board is provided with a plurality of sockets adapted to aline with the posts B' when the board D is folded upon the boards B and C.

In practice I prefer to form these sockets by attaching to the board D a plurality of rings D', the openings in the rings forming sockets, as shown at D². Upon the platform A is placed a standard A², upon which the board 65 D will rest when thrown into open position, as shown in Fig. 1. Upon the opposite end of the platform are arranged standards E, provided with suitable shoulders upon which the board C rests when opened out, and in the upper end of these standards is pivoted a board F, provided with a plurality of knobs, which knobs are adapted to enter the openings C' when the board F is folded over upon the board C. On the platform A is also arranged 70 a plurality of upright pins G, which aline with the centers of the openings C' when the board C is opened and in the position shown in Fig. 1.

The manner of operating the machine is as follows: The board C is thrown from open to 80 closed or folded position lying upon the board B, and in this position the posts B' register with the centers of the openings C', an annular space being formed between the posts and the sides of the openings, which space forms a 85 mold, and in this mold the confection is placed by hand. The board D is then folded over upon the board C, the sockets D², formed by the rings D', registering with the posts B' and the rings slightly entering the 90 mold formed by the openings C' and packing the confection. The board D is then thrown back into open position and the board C is also thrown back into open position, and the shoulders C² will prevent the fritters 95 from remaining upon the board B or falling from the board C as it is raised. As soon as the board C has been thrown into the position shown in Fig. 1 the board F is folded down upon the board C, and the 100 knobs F', entering the opening C', will force the confection therefrom, and this being in the form of rings will fall upon and encircle the pins G, and it will be obvious, therefore, that the pins G will finally be filled 105 by the rings of confection stacked upon them. It will also be obvious that removing the pins G and placing ordinary confectionery-boxes upon the platform in place of the pins the candy will be forced directly into the boxes 110

and will not have to be handled in order to be packed; but where the machine is used in shop-windows and other places for advertising purposes the use of the pins is preferable, 5 as the finished article will be stacked and displayed as it is made.

Having thus fully described my invention, what I claim as new, and desire to secure by Letters Patent, is—

- 10 1. A device of the kind described comprising a frame, a board held in said frame and provided with posts, boards hinged to opposite sides of the board first mentioned and provided respectively with openings and 15 rings adapted to aline with the posts, and a board hinged to the frame and provided with knobs adapted to enter the openings above mentioned.
- 20 2. A device of the kind described comprising a board having a plurality of posts thereon, a second board hinged to the first and having a plurality of openings, of greater diameter than the posts, and adapted to register with the posts when the boards are folded,
- 25 3. A third board hinged also to the first board having a plurality of sockets carried thereby adapted to receive the upper ends of the posts, a board adapted to fold upon the board having the openings, and knobs carried by the

last-mentioned board adapted to enter the 30 said openings and force a material therefrom.

3. A device of the kind described comprising a stationary board having posts, a board hinged to the stationary board having circular openings, a board hinged to the stationary board opposite the first-mentioned hinged board and having rings on one face, the said hinged boards being adapted to lie upon each other and coöperate together to form a mold, and a board adapted to fit upon the board 40 having the circular openings and carrying means for forcing a confection from the said openings.

4. A device of the kind described comprising a stationary board and two boards hinged 45 to the opposite ends of the stationary board, said boards being adapted to coöperate together to form a temporary mold, a plurality of vertical pins, said pins alining with circular openings in one of said boards when the said board is in an opened position, and means for forcing the material from said openings upon the pins.

ROY W. H. CRABB.
